US00RE49228E

(19) **United States**
 (12) **Reissued Patent**
 Li et al.

(10) **Patent Number:** **US RE49,228 E**
 (45) **Date of Reissued Patent:** **Oct. 4, 2022**

(54) **TROFFER-STYLE FIXTURE**(71) Applicant: **IDEAL Industries Lighting LLC**, Racine, WI (US)(72) Inventors: **Chi Man Chris Li**, N.T. (HK); **Chi Hoi Felix Mung**, Kowloon (HK); **Ho Ching Gauss So**, Kowloon (HK); **Wai To Yan**, N.T. (HK)(73) Assignee: **IDEAL Industries Lighting LLC**, Racine, WI (US)(21) Appl. No.: **29/786,731**(22) Filed: **Jun. 2, 2021****Related U.S. Patent Documents**

Reissue of:

(64) Patent No.: **Des. 807,556**
 Issued: **Jan. 9, 2018**
 Appl. No.: **29/525,657**
 Filed: **Apr. 30, 2015**

U.S. Applications:

(60) Division of application No. 29/720,033, filed on Jan. 9, 2020, now Pat. No. Re. 48,620, which is an application for the reissue of Pat. No. Des. 807,556, which is a continuation-in-part of application No. 29/481,156, filed on Feb. 2, 2014, now Pat. No. Des. 772,465, which is a continuation-in-part of application No. 14/170,627, filed on Feb. 2, 2014, now Pat. No. 10,451,253.

CLAIM

The ornamental design for a troffer-style fixture, as shown and described herein.

DESCRIPTION

FIG. 1 is a top perspective view of a light fixture according to an embodiment of the present invention.

FIG. 2 is a bottom perspective view of a light fixture according to an embodiment of the present invention.

FIG. 3 is a front elevation view of a light fixture according to an embodiment of the present invention.

FIG. 4 is a right side elevation view of a light fixture according to an embodiment of the present invention.

FIG. 5 is a rear elevation view of a light fixture according to an embodiment of the present invention.

FIG. 6 is a left side elevation view of a light fixture according to an embodiment of the present invention.

FIG. 7 is a top plan view of a light fixture according to an embodiment of the present invention; and,

FIG. 8 is a bottom plan view of a light fixture according to an embodiment of the present invention.

[Elements of the fixtures in the attached figures are in broken lines for illustrative purposes only and form no part of the claimed design.]

The broken lines depict portions of the troffer-style fixture in which the design is embodied that form no part of the claimed design.

1 Claim, 6 Drawing Sheets

Matter enclosed in heavy brackets [ ] appears in the original patent but forms no part of this reissue; matter printed in italics indicates the additions made by reissue.
